UNITED STATES PATENT OFFICE.

JOEL F. KEELER, OF CLEVELAND, OHIO.

FREIGHT-CAR LOCK.

Specification of Letters Patent No. 30,229, dated October 2, 1860.

To all whom it may concern:

Be it known that I, JOEL F. KEELER, of Cleveland, in the county of Cuyahoga and State of Ohio, have invented new and useful 5 Improvements in Freight-Car Locks; and I do hereby declare that the following is a full and complete description of the construction and operation of the same, reference being had to the accompanying drawings, making part of this specification, in which—

Figure 1 is a front view. Fig. 2 is a side view. Fig. 3 is a view of the interior seen from the side opposite that in Fig. 1. Figs. 15 4, 5, 6, 7 and 8 are sectional views which will be hereafter explained.

Like letters refer to like parts, in the several views.

The nature of my invention relates to the 20 form and structure of the lock by means of which the key hole can be sealed up either before or after locking, being self acting; that is, it can be locked without the use of the key, and without breaking the seal. It 25 is also provided with the means of being secured by a wire and lead seal, as is now done in securing the doors of freight cars.

The lock is cheap in its construction, being 30 made mostly of cast metal, strong, and not liable to get out of repair. It is made in the form of a hasp, and is therefore permanently attached to the car, and not liable to become lost. It serves the double purpose of a fastening to the sliding door of the car, and a 35 lock. It can also be applied to any kind of door, or to any place where a padlock can be used. The lock may be made of any desired form, to suit the fancy of the maker. For railroad freight cars, I find, that the form 40 presented in the accompanying drawings will be very convenient.

A, in Figs. 1, 2 and 3, represents the case, or body of the lock.

At B, there is an elongated link or opening 45 for the admission of a staple, by which the lock is secured to the body of the car, or to the sliding door, or to other object where used.

C, in Figs. 1 and 3, represents the key 50 hole. This is covered by a plate of metal C', hung upon a hinge D, Figs. 1, and 2, so that the plate C', can be lifted up like a door or lid, to admit the key into the lock, at the same time, it fits the key hole sufficiently 55 tight to prevent melted sealing wax from flowing into the lock.

Upon each side of the key hole are flanges

or lips E, for keeping the melted wax or other substance in place, while being sealed. The body of the lock is hollow, as seen in 60 Fig. 3, and is fitted to receive the spring F, seen also in a side view in Fig. 4. This spring consists of a thin bar of iron or steel, or other material, bent into the form seen in Fig. 3, or any other form, and when the 65 plate, Fig. 8, that holds it in place, is removed, it can be placed in the lock, or removed at pleasure. This plate, seen in outline in Fig. 8, is held in place by a single screw, as seen at G, Fig. 3. The recess into 70 which this plate falls, in the body of the lock, is seen in Fig. 3, and is bounded by the lines H H H H.

In Fig. 3, I represents an opening in the under side of the lock into which the catch J, 75 Figs. 6 and 7, passes, in the act of locking. In doing this, the ends F of the spring, are separated by the wedge shaped end of the catch, and fall into the depressions K, upon each side of the catch, and consequently, the 80 catch cannot be withdrawn, without separating the springs at F' F'. This catch is secured to the lintel of the door, by means of the screws or bolts passing through the flanges L L in Figs. 6 and 7, the latter of 85 which is a cross section of the lock at the opening I.

The body of the lock is provided with a conical cap M, upon the front side, Figs. 1, 2 and 7, into which the head J, of the catch 90 passes, in the act of locking.

Upon the forward end of the lock as seen at N, and upon the flange of the catch O, Figs. 2 and 6, are projections, provided with a hole each, by means of which, when the lock 95 and catch are in the position seen in Figs. 2, 3 and 6, a wire can be introduced, and sealed and stamped with a piece of lead, thus giving additional security against opening the lock or car, clandestinely.

Fig. 5, represents the key. This has two 100 nubs, which operate in pressing the springs apart, when opening the lock. When the key is removed, the springs resume the same position as when locked.

What I claim as my improvement and desire to secure by Letters Patent, is—

The spring lock and hasp in combination with the provisions for sealing the escutcheon as described.

J. F. KEELER.
